(57) **CLAIM**

The ornamental design for an electronic input device, as shown and described.

DESCRIPTION

FIG. 1 is a perspective view of a first embodiment of an electronic input device;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view of a second embodiment of an electronic input device;

FIG. 9 is a front view thereof;

FIG. 10 is a rear view thereof;

FIG. 11 is a left side view thereof;

FIG. 12 is a right side view thereof;

(Continued)

FIG. 13 is a top view thereof; and,
FIG. 14 is a bottom view thereof.

The broken lines in the figures form no part of the claimed
design.

1 Claim, 14 Drawing Sheets
